Edward C. Manchester, Attleboro, Mass., assignor to Walter W. Ross and Company, Inc., Kansas
City, Mo., a corporation of Missouri

Application October 25, 1950, Serial No. 12,717

Term of patent 14 years

(Cl. D45—10)

To all whom it may concern:

Be it known that I, Edward C. Manchester, a citizen of the United States, residing at Attleboro, in the county of Bristol and State of Massachusetts, have invented a new, original, and ornamental Design for a Finger Ring, of which the following is a specification, reference being had to the accompanying drawing, forming a part thereof.

Fig. 1 is a front elevational view of a finger ring, showing my new design.

Fig. 2 is an edge elevational view thereof; and,

Fig. 3 is a side elevational view of the finger ring.

I claim:

The ornamental design for a finger ring, as shown.

EDWARD C. MANCHESTER.
